UNITED STATES PATENT OFFICE.

JOHN W. MILLER, OF CARDIN, OKLAHOMA.

DESIGN FOR A BOX.

Application filed August 15, 1923. Serial No. 7,021. Term of patent 7 years.

To all whom it may concern:

Be it known that I, JOHN W. MILLER, a citizen of the United States of America, residing at Cardin, in the county of Ottawa and State of Oklahoma, have invented a new, original, and ornamental Design for a Box, of which the following is a specification, reference being had to the accompanying drawings, forming a part hereof.

I claim the ornamental design for a box as shown.

JOHN W. MILLER.

In the presence of—

J. J. HOLT,

ANDREW J. MILLER.
